(57) **CLAIM**

The ornamental design for a cruet set, as shown and described.

DESCRIPTION

FIG. 1 is a top and side perspective view of a cruet set showing my new design;

FIG. 2 is a view thereof with the parts disassembled; and, FIG. 3 is a view similar to FIG. 1 but with one part removed for clarity of illustration.

1 Claim, 3 Drawing Sheets

FIG. 1

FIG. 2

FIG. 3
